DESIGN FOR CARPET.

Design No. 7,300, dated March 31, 1874

UNITED STATES PATENT OFFICE.

HUGH S. KERR, OF PHILADELPHIA, PENNSYLVANIA, ASSIGNOR TO JAMES KITCHENMAN, OF SAME PLACE.

DESIGN FOR CARPET.

Specification forming part of Design No. 7,300, dated March 31, 1874; application filed March 21, 1874.
[Term of Patent 3½ years]

To all whom it may concern:

Be it known that I, HUGH S. KERR, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

I claim as my invention—
The configuration of the design hereunto annexed, when applied to carpeting.

HUGH S. KERR.

Witnesses:
JAMES CHESTNUT,
C. QUIRNER.
